RAILWAY BRAKING APPARATUS

Kenneth J. J. McGowan, Pittsburgh, and Herbert L. Bone, Forest Hills, Pa., assignors to The Union Switch & Signal Company, Swissvale, Pa., a corporation of Pennsylvania

Application July 30, 1940, Serial No. 348,592

6 Claims. (Cl. 188—62)

Our invention relates to railway braking apparatus, and particularly to that class of braking apparatus known as inert car retarders.

More particularly, our present invention relates to inert car retarders of the type described and claimed in Letters Patent of the United States No. 2,104,606, granted to Herbert L. Bone on January 4, 1938, for Railway braking apparatus. In the said car retarders, the braking bars are supported for swinging movement toward and away from a track rail by means of levers pivotally mounted at their lower ends on the base flange of the track rail by means of recesses which receive the base flange. The levers are biased toward the rail to their braking positions by means of spring assemblies each of which includes a spring bolt extending through aligned clearance holes provided in the levers and in the rail web and a spring disposed on this spring bolt, and means in addition to the spring assemblies are provided to hold the lower ends of the levers in engagement with the rail flange when no car is in the retarder.

One object of our present invention is to simplify the construction, and thereby decrease the cost of manufacture and maintenance, of car retarders of the type disclosed in the said Bone patent.

According to our invention, we accomplish this object by so constructing the spring assemblies that they not only serve to bias the levers to their braking positions, but also serve to exert on the associated lever when no car is in the retarder, a mechanical couple the effect of which is to hold the lever in proper engagement with the rail flange or other support without the necessity for the other means which have heretofore been provided for this purpose.

Other objects and characteristic features of our invention will become apparent as the description proceeds.

We shall describe two forms of car retarders embodying our invention, and shall then point out the novel features thereof in claims.

In the accompanying drawings, Fig. 1 is a vertical sectional view showing one form of inert car retarder embodying our invention. Fig. 2 is a side view of the retarder shown in Fig. 1 as it appears when viewed from the right in Fig. 1. Figs. 3 and 4 are views similar to Figs. 1 and 2 showing a modified form of the retarder illustrated in Fig. 1.

Similar reference characters refer to similar parts in each of the several views.

Referring first to Figs. 1 and 2, the reference

5 character 1 designates one track rail of a stretch of railway track over which the wheels of cars which are to be retarded by the retarder are adapted to pass, one such wheel 2 being shown in dot and dash lines in the drawings.

The rail 1 is supported at spaced points on rail supports 3, and associated with each rail support is a spring unit U which serves as a means for biasing a braking bar B, which extends parallel to the rail, to a braking position in which it will frictionally engage the wheels of cars traversing the rail 1. The braking bar B comprises, as usual, a brake beam 4 and a brake shoe 5.

15 The spring unit U in the particular form illustrated comprises a vertically extending cast lever 6 disposed at the outer side of the rail 1, and provided at its lower end with a rounded bearing surface 6a which rests on the base flange 3a of the support 3 between upstanding pairs of laterally spaced lugs 7 and 8. As will appear presently, the lever 6 is intended to swing toward and away from the rail 1 about the bearing surface 6a as a fulcrum, and the lugs 7 and 8 cooperate with the opposite sides of the lever to loosely limit the distance through which the lower end of the lever is free to move laterally toward or away from the rail 1. Excessive vertical displacement of the lever 6 is prevented by

20 a lug 3b which is cast on the support 3, and which extends loosely into, and cooperates with, the lower end of a rectangular opening 6b which is formed in the lever intermediate its ends. The lug 3b also assists in positioning the lever 6 longitudinally relative to the rail. This method of pivotally supporting the lever 6 eliminates the necessity for any extensive machining operations, and enables the cost of the retarder to be reduced to a minimum.

25 40 45 50 The opening 6b aligns at its upper end with an opening 10 provided in the web of the rail 1, and a vertical slot 3c provided in an upstanding arm 3d formed on the support 3 on the side of the rail opposite to the lever 6. The slot 3c and openings 10 and 6b loosely receive a T-headed spring bolt 9, the head 9b of which fits between laterally spaced ribs 3e formed on the arm 3d in such manner that the bolt is prevented from rotating about its axis. The bolt, however, is intended to rock in a vertical plane a slight amount about the region of contact between the head 9a and the arm 3d on opposite sides of the slot 3c, and to this end the forward faces of the two ends of the head are rounded in the manner shown.

Mounted on the bolt 9 at the outer side of the lever 6 are an inner spring seat 11, a compressed coil spring 12, an outer spring seat 13 and a nut 14. The spring seat 11 bears at its inner end against the lever 6 on opposite sides of the opening 6b, and to facilitate rotation of the lever relative to the spring seat, the inner end of the spring seat is provided on opposite sides of the bolt with horizontally aligned rounded bulges 11a, and the lever is provided on opposite sides of the opening 6b with horizontally aligned grooves 6d, which grooves receive the bulges 11a. The inside spring seat is also provided on the side opposite to the bulges 11a with a circular boss 11b which serves to center the inner end of the spring relative to the bolt.

The outer spring seat 13 is provided with a laterally projecting skirt portion 13a which cooperates with the spring 12 at its outer end to hold it in a centered position relative to the spring bolt 9, with two diametrically opposite apertured lugs 13b and 13c, and with a boss 13d. Two bolts 15 and 16 extend with some clearance through the apertures in the lugs 13b and 13c, and through openings 6e and 6f formed in the lever 6 on opposite sides of the spring bolt 9 and are provided at their inner ends with nuts 17 which fit in recesses 6h formed in the inner face of the lever. The bolts 15 and 16 and nuts 17 constitute a means for providing the spring 12 with an initial compression for a purpose which will appear presently, and the recesses which receive the nuts 17 serve to prevent rotation of the nuts, whereby the desired initial compression of the spring 12 may be obtained by rotating the bolts by means of their heads since the bolt heads are more accessible than the nuts. After the desired initial compression of the spring 12 has been obtained, the parts are locked in their adjusted positions by a wire 24 threaded through holes in the heads of the bolts, and formed into a loop which surrounds the boss 13d of the spring seat 13.

The boss 13d on the spring seat 13 is provided on opposite sides of the spring bolt 9 with rounded bulges 13e which cooperate with rounded recesses 14a provided on the inner face of the nut 14 to automatically lock the nut against unwanted rotation.

The lever 6 is further provided with an L-shaped upper surface 6g which supports the brake beam 4, and with a horizontal shoulder 6j which partly supports the brake shoes 5 of the braking bar. The brake beam 4 is secured to the lever by means of two vertical bolts 23 which extend downwardly through longitudinally spaced clearance holes in the brake beam and aligned holes in the lever, and which are provided at their lower ends with lock washers 18 and nuts 19, while the brake shoe 5 is secured to the lever by means of a pair of horizontally disposed bolts 20 which extend through aligned holes in the brake shoe and in the lever and are provided at the outer side of the lever with lock washers 21 and nuts 22.

The parts are so proportioned that lever 6 is biased by gravity to swing in a clockwise direction, as viewed in Fig. 1, but that this biasing force is insufficient to compress the spring 12 beyond its initial compression. It will be apparent, therefore, that when no car is traversing the track rail within the limits of the car retarder, the spring bolt 9 will be held in the position in which its head 9a engages the arm 3d on the rail support 3, and the lever 6 will be

biased toward the rail by the spring 12 to a position which depends upon the adjustment of the nut 14. The nut 14 will usually be so adjusted that when no car is passing through the retarder, the lever 6 will occupy a position in which the brake shoe 5 projects into the path of car wheels traversing the rail 1, and it will be seen, therefore, that when a car enters the retarder, the wheels will engage the brake shoe 5 and will thereby rotate the lever 6 in a clockwise direction from its normal position to the position in which it is shown in the drawing, which latter position we shall term its braking position. This rotation of the lever moves the spring seat 11 toward the right, as viewed in Fig. 1, to a position in which the spring 12 becomes compressed beyond its initial compression, and also causes a rotating motion between the points of contact of the lever with the spring seat. This rotation of the lever also causes the spring bolt 9 to swing downwardly a slight amount about the points of contact between its head 9a and the arm 3d, as will be obvious. The braking forces which are exerted on the car will of course depend upon the stiffness and the amount of initial compression of the spring 12, and may be adjusted by adjusting the bolts 15 and 16 in the manner pointed out hereinbefore.

It should be particularly pointed out that in a car retarder of the type described it is essential that the lower end of the lever 6 should remain in firm contact with the lugs 7 when no car is in the retarder for three reasons. In the first place, if the lower end of the lever is allowed to swing out of engagement with the lugs 7 when no car is in engagement with the retarder, the position which the upper end of the lever, and hence the brake shoe 5, will assume is likely to vary, which makes it difficult to adjust the retarder. In the second place, if the lower end of the lever is allowed to swing away from the rail, the recoil of the spring 12 when a car leaves the retarder is likely to cause the brake shoe 5 to swing closer to the rail than is desirable, and as a result when a car next starts to enter the retarder, it will strike the end of the brake shoe with a greater force than intended, and thereby damage the retarder. In the third place, if the lower end of the lever is out of engagement with the lugs 7 when a car starts to enter the retarder, the force set up by the wheels striking the brake shoe will swing the lower end of the lever into engagement with the lugs with a hammerlike blow, which will cause excessive stress and wear.

In accordance with our present invention we retain the lower end of the lever in the desired position by locating the holes 6e and 6f in the lever through which the bolts 15 and 16 which adjust the initial compression of the spring 12 pass in such positions that the nuts 17 will engage the lever along a horizontal line of contact which is disposed vertically above the axis of the spring bolt 9. With the parts arranged in this manner, when no car is in the retarder, the spring 12 will apply to the lever on the side nearest the rail a force acting along a line disposed above and inclined to the axis of the bolt 9 which force, together with that acting on the outer side of the lever along the axis of the bolt, produces on the lever a mechanical couple which is effective to maintain the lower end of the lever in firm contact with the lugs 7.

If it is desired to render the retarder inactive for any reason, this may be done by backing

off the nut 14 a few turns. This will allow the lever to swing due to its gravity bias to a position in which the brake shoe 5 is out of the path of car wheels traversing the rail 1.

It should be pointed out that when the brake shoe 5 becomes worn, this wear can be compensated for by adjusting the nut 14, as will be obvious. It should be particularly noted that this adjustment will not affect the forces which hold the lower end of the lever in engagement with the lugs 7.

Referring now to Figs. 3 and 4, in the modified form of retarder here shown the braking bar B is supported for swinging movement toward and away from the rail 1 by means of a cast lever 25 provided at its lower end with a channel shaped recess 25a which loosely receives the base flange of the rail 1 in such manner that the lever is free to pivot about the base flange as a fulcrum. The brake beam 4 and brake shoe 5 of the braking bar are secured to the lever 25 by means of bolts 20 and 23, respectively, in the same manner as they are secured to the lever 6 in Figs. 1 and 2.

Formed in the lever 25 in axial alignment with an opening 10 in the rail web is an opening 25b, and extending with clearance through the aligned openings 10 and 25b is a spring bolt 26, the left-hand end of which, as viewed in Fig. 3, is provided with a bearing sleeve 27 and a nut 28, and the right-hand end of which is provided with an inner spring seat 29 similar to the spring seat 11 in Figs. 1 and 2, a compressed coil spring 12, an outer spring seat 30 and a nut 31.

The bearing sleeve 27 is provided with a depending portion 27a which cooperates with the base flange of the rail to prevent rotation of the sleeve relative to the spring bolt in response to rotation of the nut 28, and with rounded surfaces 27b on opposite sides of the bolt about which the sleeve is intended to roll to permit the spring bolt to rock in response to rotation of the lever 25. The outer end of the bearing sleeve is provided with rounded bulges 27c which enter correspondingly shaped recesses 28a provided in the adjacent face of the nut. The normal position of the lever, that is to say, the position when no car is passing through the retarder, is determined by adjusting nut 28, which nut also provides a means for adjusting for brake shoe wear, and the cooperating bulges 27c and recesses 28a provide a convenient means for locking the nut 28 against rotation to prevent loss of adjustment due to vibration and the like.

To permit adjustment of the initial compression of the spring 12, the spring bolt 26 is provided between the rail and the lever with a shoulder 32 which, when no car is in the retarder, engages the inner face of the lever at rounded portions 25d formed on the lever on opposite sides of the bolt. Adjustment of the initial compression of the spring 12 may be made by means of the nut 31, as will be obvious.

The operation of the retarder as a whole when constructed as shown in Figs. 3 and 4 will be apparent in general from the foregoing description of Figs. 1 and 2. It should be particularly pointed out, however, that in accordance with our present invention we so locate the rounded portions 25d which are provided on the lever that the points of contact between the shoulder 32 and these rounded portions when no car is in the retarder will occur along a horizontal line disposed vertically above the axis of the bolt 26, whereby when no car is passing through the retarder, the spring 12 will apply to the

lever on the side nearest the rail 2 force acting along a line disposed above and inclined to the axis of the bolt 26, which force, together with that acting on the outer side of the lever along the axis of the bolt, produces on the lever a mechanical couple of forces which are effective to maintain the lower end of the lever in firm engagement with the rail flange without the necessity for any other means for this purpose. It should also be pointed out that adjustment of the nut 28 to compensate for brake shoe wear will not materially affect this couple, so that when the proper initial compression of the spring 12 has once been obtained, it is not necessary thereafter to further adjust the nut 31.

Although we have herein shown and described only two forms of car retarders embodying our invention, it is understood that various changes and modifications may be made therein within the scope of the appended claims without departing from the spirit and scope of our invention.

Having thus described our invention, what we claim is:

1. Railway braking apparatus comprising a lever disposed at one side of a track rail for swinging movement toward and away from the rail and provided at its upper end with a braking bar extending parallel to the rail, means including a spring bolt and a spring disposed on said bolt for normally exerting on said lever a force which biases said lever to a braking position in which said braking bar will frictionally engage the wheels of a car traversing said rail, and other means carried in part by said bolt and in part by said lever and effective when no car wheel is engaging said braking bar for causing said spring to exert on said lever a mechanical couple which is effective to maintain the lever in firm engagement with the point about which it swings.

2. Railway braking apparatus comprising a lever disposed at one side of a track rail for swinging movement toward and away from the rail and provided at its upper end with a braking bar extending parallel to the rail, means including a spring bolt and a spring disposed on said bolt for normally exerting on said lever a force which biases said braking bar to a position in which it will frictionally engage the wheels of a car traversing said rail, and means carried by said bolt and engaging said lever at a point offset from the axis of said bolt when no car wheel is engaging said braking bar for applying to said lever by means of said spring along a line inclined to the axis of the bolt a force which together with the spring force acting on the lever along the axis of the bolt produces a mechanical couple which is effective to maintain said lever in firm contact with the point about which it swings.

3. Railway braking apparatus comprising a lever disposed at one side of a track rail for swinging movement toward and away from the rail, said lever being loosely supported at a point below the rail web by means which limits movement of the lever toward the rail at its point of support, means including a spring and a spring bolt for applying to said lever a force which urges said lever toward the rail to a predetermined position, said lever being biased away from the rail by gravity, and other means carried in part by said lever and in part by said bolt for applying to said lever by means of said spring along a line disposed above and inclined

to the axis of said bolt a force which together with the force applied to said lever along the axis of said bolt exerts on said lever when no car wheel is engaging said braking bar a torque which urges said lever toward the rail at its point of support to limit wear between the parts.

4. Railway braking apparatus comprising a lever loosely pivotally supported at its lower end at one side of a track rail for swinging movement toward and away from the rail and provided at its upper end with a braking bar extending parallel to the rail, said lever being provided with an opening which aligns with an opening provided in the web of the track rail, a spring bolt extending through said openings with clearance and provided at the end disposed at the outer side of said lever with a nut and at the opposite end with means for preventing axial movement in one direction, a spring disposed on said bolt between said lever and said nut for applying to said lever at its outer side a force which biases the lever toward the rail to a position in which said braking bar will frictionally engage the wheels of cars traveling said rail, a spring seat disposed on said bolt and engaging the outer end of said spring, and means including two bolts extending loosely through apertures provided in said spring seat and openings formed in said lever and carrying means engaging said lever along a horizontal line disposed above the axis of said spring bolt for at times applying to said lever by means of said spring a mechanical couple which is effective to prevent lost motion between said lever and its support.

5. Railway braking apparatus comprising a track rail mounted on a rail support and provided with an opening in the rail web, a lever resting at its lower end on said rail support between spaced lugs which loosely limit movement of the lower end of said lever toward or away from the rail and provided at its upper end with a braking bar for frictionally engaging the wheels of a car traversing said rail, said lever being provided with an opening aligning with the opening in the rail web, an arm on said rail support on the side of the rail opposite to said lever, said arm being provided with a slot aligning with the openings in said rail web and said lever, a bolt extending through said slot and said openings and provided with a head which engages said arm at the side farthest away from the rail, a nut screwed onto said bolt at the end

opposite to its head, a spring disposed on said bolt between two spring seats one of which engages said nut and the other of which engages said lever at its outer side, diametrically opposite apertured lugs provided on the spring seat which engages said nut on opposite sides of said bolt, holes formed in said lever on opposite sides of the opening which receives said spring bolt at points located vertically above the axis of said spring bolt, and other bolts passing through the apertures in said lugs and the holes in said lever and provided with means engaging the inner face of said lever along a line disposed above the axis of said bolt, whereby a force is at times applied by means of said spring and said other bolts to said lever at the side nearest the rail along a line inclined to the axis of said spring bolt which force together with the spring force acting along the axis of the bolt produces a mechanical couple which is effective to maintain the lower end of said lever in firm contact with the lugs which limit movement of this end of the lever toward the rail.

6. Railway braking apparatus comprising a lever disposed at one side of a track rail and provided at its lower end with a recess which receives the base flange of the rail in such manner that the upper end of said lever is free to swing toward and away from the rail about the base flange as a fulcrum, said lever being provided intermediate its ends with an opening which aligns with an opening provided in the web of the track rail, a braking bar secured to the upper end of said lever, a spring bolt extending with clearance through said opening and provided at each end with a nut, a spring disposed on said bolt between said lever and the adjacent nut and effective to bias said lever toward the rail to a position in which said braking bar will frictionally engage the wheels of cars traversing said rail, and means on said bolt between the rail and said lever adapted to engage the inner side of said lever along a line disposed above the axis of said bolt when no car wheel is in engagement with said braking bar to cause said spring to exert on said lever a mechanical couple which holds the lower end of the lever in engagement with the base flange of the rail.

KENNETH J. J. McGOWAN,
HERBERT L. BONE.
